GOLF BALL TEEING DEVICE

Elmer E. Goehler and Paul Amort,
Portland, Oreg.

Application March 4, 1935, Serial No. 9,229

17 Claims. (CL 273—33)

Our invention relates to apparatus for successively presenting a ball properly teed in driving position as long as a player cares to continue driving them and presents numerous advantages over apparatus heretofore known for the purpose, chief among which are the following:—

By holding the ball to the tee under the influence of a slight vacuum we are enabled to use a tee of smaller diameter, hence greater flexibility and with less liability of the effect of the drive being modified by resistance of the tee when the ball is struck.

Using a tee of small diameter, great flexibility and holding the ball thereon by vacuum of small degree permits the ball being touched by the player as he addresses the ball preparatory to his driving stroke, without displacing it.

Holding the ball to the tee by slight vacuum makes available an ideal force for operating control apparatus for motor devices to reciprocate the tee, the impulsion of air when the vacuum is broken by the drive.

Vacuum apparatus of small capacity being required for each tee operated, a moderate sized vacuum producing device may operate a considerable number of tees and may be widely spaced therefrom resulting in an entirely noiseless operation of the device to the end that the player is not distracted as by the hum of an individual motor of the electric type such as has been heretofore used.

Apparatus of the character described herein-after is little or nothing subject to interference by moisture, requires no periodic oiling or other attention, made of inexpensive materials and not requiring extra critical workmanship it can be distributed for a small fraction of the maker's cost of apparatus heretofore known, thus making it available for a much larger use.

Realization of the advantages heretofore stated and others that will be apparent from this disclosure is the purpose of our present invention.

Drawings accompany and form a part of the disclosure herewith, illustrating the best form of apparatus as now contemplated but it is to be understood that they are illustrative and not limiting and that by certain obvious changes, air pressure can be substituted for vacuum in the main motor; or any motive force can be substituted for either air pressure or vacuum in the main motor upon suitable modification of the control device which will still be itself controlled by our vacuum tee, hereinafter described in detail.

In the drawings:—

Fig. I is a longitudinal vertical section of the preferred form of our invention, partly in section and showing the apparatus in its normal or de-energized position;

5

Fig. II is a view taken on the same plane as that in Fig. I, sectioned in a different manner, and shows the apparatus energized and holding a golf ball in driving position relative to a playing field;

10

Fig. III is a section on the line III—III of Fig. II;

Fig. IV is a section on the line IV—IV of Fig. II; and

Fig. V is a section taken as indicated by the line V—V in Fig. II.

Referring to Fig. II. A tee member 1, made of highly resilient soft rubber, has a vacuum cup 2, formed on its ball engaging end, and an internal passageway 3, which communicates with the bent tube 4, which also constitutes the arm for raising a golf ball G, from storage to playing position.

Flexible tubes 5 and 6, are in communication with a vacuum producing device not shown and the tube 5, is connected to the bent tube 4, at 6. Thus in the position shown in Fig. II, vacuum of small degree will exist in the hollow of the tube 4, designated by 4a, and this will be applied to the golf ball G, shown resting on the vacuum cup 2, and will also exist in the chamber 7. The amount of vacuum required is quite low.

Referring now to Fig. I and assuming that vacuum effect is about to be applied. If the vacuum cup 2 were open, that is no ball G in place, vacuum would be satisfied through the passageway 3, 4a, 6, etc. But as soon as a golf ball takes its place on the vacuum cup 2, it closes the passageway 3, not necessarily perfectly air tight, but sufficiently so that vacuum will appear in the chamber 7. This causes a deflection of the diaphragm 8, from the position shown in Fig. I to that shown in Fig. II, which moves the slide valve 9, and causes the ports 10 and 11, to be placed in communication by relative movement of the D slot 12.

As before mentioned the flexible tube 6, is connected to the same vacuum source as 5, and vacuum therefore will be felt through the passageway 6a, be transferred by the D slot 12 to the port 10 and thence through the tube 13 to the rubber bellows 14, which partially collapses from the position shown in Fig. I to that shown in Fig. II.

55

The bellows 14, is anchored at 15 so that it is capable, at that point, of a relatively small longitudinal movement, the purpose of which will be hereinafter explained. The whole apparatus or head 16, is pivoted at 17. The axis of the pivot 17 is approximately at right angles to the axis of the tube 4.

Collapsing of the bellows 14, after the manner indicated, therefore swings the head 16, on the pivot 17, and raises the tee 1, from the position shown in Fig. I to that shown in Fig. II, carrying the golf ball G with it.

A stop 18, which may be conveniently made adjustable, limits the upward movement of the tee 1, by arresting the movement of the tube 4. It is evident that the vacuum being maintained on 5 and 6, and the golf ball G being elevated to the position shown in Fig. II, the ball will remain there until driven from the tee 1, or otherwise removed.

As soon as the golf ball G is struck or otherwise displaced from the vacuum cup 2, vacuum in the vacuum cup 2, and in all passages connected thereto, and particularly in the chamber 25 1, is satisfied by the impulsion of air through the passageway 4a. The diaphragm 8, being made of resilient rubber, will resume the position shown in Fig. I, moving the slide valve 9, so that the D slot 12 is out of registration with the port 11 and places the port 10 in operative registration with the vent port 20, which then satisfies the vacuum in the interior of the bellows 14, which accordingly relaxes and the tee 1, and its connected parts drop to the position shown in Fig. I, 30 ready to receive another ball if any be present in the chute 21. Thus the cycle may be repeated indefinitely, smoothly and noiselessly so long as the vacuum is maintained by the vacuum producing means and so long as balls are available to 35 consecutively take their places on the vacuum cup 2, as the tee 1, drops into ball receiving position, thence to be raised to ball delivering position and held there until driven therefrom.

The anchor 15, of the bellows 14, is connected 45 to reachrods 25 and 26, which are in turn connected to the plate 27, provided with cam slots 28 and 29. These cam slots 28 and 29 engage the lower ends of gate wires 30 and 31, which are pivoted to swing at 32.

50 In Fig. V the gate, composed of the wires 30 and 31, is shown closed, which will be the same position indicated in Fig. II with the ball in raised position. It opens to admit a ball to the tee as the bellows 14, finishes its relaxing movement.

The plate 27, containing the cam slots 28 and 60 29, is arranged to move very easily and when vacuum energy starts to collapse the bellows 14, it will move first and close the gate wires 30 and 31 together to stop additional balls from rolling down the chute 21. When it has reached the limit of its movement, then additional collapsing movement of the bellows 14 will swing the head on its pivot and raise the tee 1 as hereinbefore described, and obviously since the plate 27 moves first upon energizing of the bellows 14, it will be moved last when the tee drops to ball receiving position.

A vent 40, communicates with the diaphragm chamber on the opposite side of the diaphragm 8, from the chamber 1, so that influence felt in the chamber 1, will not be impaired or interfered with.

70 Almost innumerable modifications may be made without departing from the operative principles

hereinbefore described. We therefore do not desire to limit ourselves to the specific device shown, nor operating after the specific manner shown, but what we claim and desire to secure by Letters Patent, is,—

5 1. In a golf apparatus, a movable tee, a vacuum ball holder on the tee that is adapted to retain a ball on said tee and vacuum producing means operatively connected to the ball holder through the tee.

10 2. In golf apparatus, a reciprocable tee arranged to hold a ball in driving position by vacuum and means movable to reciprocate said tee and replace a ball driven therefrom, a reciprocation cycle of said movable means being initiated by breaking the vacuum in driving the ball from the tee.

15 3. Golf ball apparatus for successively replacing a ball on a tee in driving position, defined in part as a reciprocable tee member, a vacuum ball holder terminating said tee and vacuum producing means operatively connected to said ball holder.

20 4. Golf apparatus comprising a reciprocable tee, vacuum operated means for reciprocating said tee, pneumatic valve means for controlling said last named means and means whereby atmospheric pressure is rendered effective to move said pneumatic valve when a ball is driven from said tee.

25 5. In golf apparatus, a reciprocable tee adapted to hold a ball in driving position and pneumatic means for reciprocating said tee to replace a driven ball, pneumatic control means for said reciprocating means and means operable by air impulsion to move said control means upon breaking contact of a ball with said tee.

30 6. Golf apparatus defined in part as a resilient tee, a vacuum cup in ball holding position on said tee and vacuum producing means connected to said vacuum cup.

35 7. Golf apparatus for automatically replacing a ball driven from a tee, comprising in combination a reciprocable tee, a pneumatic motor for reciprocating said tee, a valve for controlling operation cycles of said motor and pneumatic means for moving said valve to control said motor that are rendered operative by breaking contact of a ball with said tee.

40 8. Golf apparatus for automatically replacing a ball driven from a tee, comprising in combination a vacuum motor, a tee reciprocable by said motor, a valve apparatus adapted to control said motor to reciprocate said tee by cycles and vacuum means for retaining a ball on said tee, the said valve being movable by impulsion of air when vacuum is broken by driving a ball from said tee.

45 9. Golf apparatus for automatically replacing a ball driven from a tee, comprising in combination a pneumatic motor, a tee reciprocable by said motor, a valve apparatus adapted to control said motor to reciprocate said tee by cycles and vacuum means for retaining a ball on said tee, the said valve being movable by impulsion of air when vacuum is broken by driving a ball from said tee.

50 10. Golf apparatus for automatically replacing a ball driven from a tee, comprising in combination a motor, a tee reciprocable by said motor, control apparatus for said motor that limits its movement to one reciprocation cycle of the tee and vacuum means for retaining a ball on said tee, the said control apparatus being arranged to act by impulsion of air when vacuum is broken by driving a ball from the tee.

11. Golf apparatus comprising a tee reciprocable to successively replace balls driven therefrom, pneumatic motor means for reciprocating said tee to replace a ball driven therefrom and stop with the ball in driving position, control means for said motor and vacuum means for retaining a ball on the tee, the said control means being adapted to move to control said motor under the influence of air impulsion when a ball is driven from the tee.

12. Golf apparatus comprising a tee automatically movable to ball receiving position and reverse to ball driving position after receiving a ball, vacuum ball holding means on the tee and vacuum means connected to said ball holding means, the reverse movement of the tee to driving position being dependent upon closure of the vacuum ball holding means by a ball and establishment of vacuum thereunder.

13. Golf ball apparatus for cyclic reciprocation of a golf tee between a ball receiving position and ball striking position, including means for stopping the tee in driving position until a ball is driven therefrom, said means including a vacuum passage that is closed by the ball and motor control apparatus operatively connected to said vacuum passage that is movable under the influence of vacuum in said passage to energize a motor.

14. Golf apparatus comprising a golf tee, vacuum ball retaining means on the ball engaging end of said tee and vacuum producing means operatively connected to said ball retaining means.

15. In a teeing device, a reciprocable ball holding tee, pneumatically operated means for reciprocating said tee, pneumatic power means operatively connected to the tee and a conduit between said power means and the ball holding portion of said tee that is arranged to be substantially closed when a ball is in position on the ball holding portion of the tee.

16. In a golf ball teeing device, a reciprocable tee, a vacuum bellows arranged to reciprocate said tee, control means for said bellows and means that are rendered operable to energize said control means by driving a ball from the tee.

17. A teeing device defined in part as a reciprocable tee, a vacuum bellows arranged to reciprocate said tee, control means for said bellows, vacuum producing means positioned to activate said bellows through said control means, the said control means being arranged to cause vacuum activation of said bellows when a ball is in place on said tee.
